UNITED STATES PATENT OFFICE.

LUCIAN M. ZELL, OF BOSTON, MASSACHUSETTS, ASSIGNOR TO THE AMERICAN GEM COMPANY, OF MAINE.

DESIGN FOR A BROOCH.

SPECIFICATION forming part of Design No. 32,523, dated April 17, 1900.

Application filed February 5, 1900. Serial No. 4,142. Term of patent 3 $\frac{1}{2}$ years.

To all whom it may concern:

Be it known that I, LUCIAN M. ZELL, a citizen of the United States, residing at Boston, in the county of Suffolk and State of Massachusetts, have invented and produced a new and original Design for a Brooch, of which the following is a specification, reference being had to the accompanying drawing, forming part hereof, which is a plan view of a brooch showing my new design.

As shown in the drawing, the leading or material feature of my design consists of a semicircular or crescent-shaped row of stones or jewels, the stones of which are nearly circular in outline, as seen from the front, and are graduated in size, the largest being in the

center. Furthermore, outside or below this row of nearly-circular stones is arranged parallel to it another row of stones, which are pear-shaped and equal in number to the row of circular stones, each of these pear-shaped stones hanging by its small end from one of the round stones.

The same design can evidently be used for many different articles of jewelry. 25

What I claim is—

The design for a brooch as herein shown and described.

LUCIAN M. ZELL.
